ENEMA APPARATUS

Mary E. Stack, Seattle, Wash.

Application March 4, 1947, Serial No. 732,302

6 Claims. (Cl. 128—227)

1

This invention relates to apparatus for use in connection with administration of enemas or other internal baths or irrigations.

While administration of an enema is a necessary treatment in probably a majority of cases of sick people, yet enema apparatus now in practical use has not been improved for years.

Prior art apparatus employed in this particular field generally comprised a water bag, tube, and a hose connection between the water bag and the tube. A difficulty in such prior art apparatus was that pressures were built up within the patient and need of relief therefrom necessitated the interruption of the enema and then it was necessary to start the enema all over again after discharge of gas, liquid, and fecal matter.

Also prior art enema apparatus was not of a design so that adequate and painless enemas could be given. It is an object of my invention to provide an improved appliance for use in giving an adequate and efficient enema which will at the same time make the application of medicated solutions in the colon less painful and more effective because of less pressure on delicate tissues. Properly trained personnel with the use of this apparatus can readily give an effective enema without causing pain, distension or overloading of the colon.

It is a further object of my invention to provide apparatus which will readily permit the giving of an adequate enema even in cases where a colon has static ataxia, poor muscular action and is lazy.

Other objections found in the prior art included the use of a single tube and the absence of inlet and discharge openings in a tube which tube could be left in the colon of a patient at all times during the enema or other internal irrigation treatment.

It is an object of my invention to provide a tubular member which can be inserted in the colon of a patient and which can be maintained there at all times during the enema or other internal irrigation treatment.

It is a further object of my invention to provide a receptacle for clean or fresh treating solution (hereafter called clean can); a receptacle for slightly soiled treating solution (hereafter called soil can); and a third receptacle for containing liquid and other matter which is not again to be used (hereafter called discharge can).

It is a further object of my invention to provide valve means disposed between the various mentioned cans and the tube which is to be inserted into the colon of a patient so that any one

of a plurality of positions can be selected during the treatment of the patient. As the selected medicants which are added to provide the original treating solution from no part of the present invention, they will not be discussed. However any treating solution desired by the physician or nurse can be readily administered by the apparatus of my invention.

The various predetermined positions which may be selected will be discussed hereafter in detail; however, a normal operating position of structure embodying my invention, is to provide for free passage from the clean can to the patient and free passageway from the patient to the soil can.

Another object of my invention is to provide a position so that immediate gas relief can be provided for the patient at all times without requiring removal of the tube from the patient.

Another object of the invention is to provide auxiliary pressure providing means so that, when necessary, auxiliary pressure can be provided to stimulate the organs involved so that free flow of liquid is possible.

Another object of my invention is to provide apparatus having suitable indicia so that the operative positions of the several parts are readily apparent.

Another object of my invention is to provide apparatus which may be readily sterilized.

The above mentioned general objects of my invention together with others inherent in the same are attained by the device illustrated in the accompanying drawings throughout which like reference numerals indicate like parts:

Figure 1 is a somewhat diagrammatic view in elevation and with parts broken away illustrating the apparatus of this invention;

Fig. 2 is a detached elevational view of the valve looking in the direction of broken line 2—2 of Fig. 1;

Fig. 3 is a sectional view with parts in elevation, taken substantially on broken line 3—3 of Fig. 2;

Fig. 4 is an exploded view showing the several parts of the valve in elevation and with a fragment of the casing broken away;

Fig. 5 is an enlarged fragmentary view in elevation of the tube member shown in Fig. 1 which is to be inserted into the colon of the patient and is a view taken substantially in the direction of broken line 5—5 of Fig. 1; and

Figs. 6 to 12 inclusive are sectional views showing the positions of the various ports and passageways in the valve means, wherein each figure

represents one valve setting and wherein the view to the left in each figure is taken substantially on broken line $y-y$ of Fig. 3 and the view to the right in each figure is taken substantially on broken line $x-x$ of said Fig. 3.

In the drawings, the clean can 13 is shown formed integrally with the soil can 14 for convenience of manufacture. However, it is to be expressly understood that the two cans 13 and 14 may be formed separately. As liquids are designed to always flow in a direction from the clean can 13 toward the soil can 14, the bottom of the clean can 13 is elevated above the bottom of the soil can 14 and thus the liquid level in the clean can 13 can always be maintained above any liquid level in the soil can 14. On the average, the maximum capacity of a patient for liquids during an enema is about 3 pints and thus the volume capacity of the soil can 14, below the floor of the clean can 13, may be slightly over 3 pints and thus at all times the liquid level in the soil can 14 cannot reach the liquid level in the clean can 13. Clean enema treating solution is first inserted in the clean can 13 and passes via conduits 16 and 21 to the colon of a patient. Soiled enema treating solution passes from the colon of the patient via conduits 22 and 17 to the container 14 for soiled enema treating solutions. Due to the capacity of the soiled can 14 below the floor level of the clean can 13, solutions can flow from the clean can 13 through the passageways mentioned and to the soiled can 14. We always have, because of the construction mentioned, a tendency of the liquids to flow in the direction mentioned. However, as the levels of liquids in the cans 13 and 14 approach each other, the difference in head between the liquids in cans 13 and 14 diminishes and a tendency to flow ceases. However, because of the volume capacity of the soiled can 14 below the clean can 13 there is a tendency of liquids to flow from can 13 to can 14 until the liquids approach a common elevation and the differential in head is eliminated. Obviously, there is no tendency, in view of the construction mentioned, for liquids to flow from the soiled can 14 toward and into the clean can 13.

The valve member, indicated generally by 15, is connected by flexible hose members 16 and 17 with the clean and soil cans 13 and 14. The valve member 15 comprises an outer casing 18 having a hanger 19 so that the valve member 15 may be suitably supported in suspension at any desired elevation. The hanger 19 is connected to any fixed support such as support 20. Also the clean and soil cans 13 and 14 are provided with any suitable means (not shown) so that they can be adjustably supported by a fixed supporting means at any desired elevation above the valve member 15.

The valve member 15 is provided with suitable nipples so that flexible hose members 16, 17, 21, 22 and 23 are connected respectively with ports 24, 25, 26, 27 and 28 respectively in casing 18. Disposed between port 26 and flexible hose 21 is a rubber bulb 29 and disposed between port 27 and flexible hose 22 is another rubber bulb 30. These rubber bulbs are of the usual type which upon squeezing the same provide additional air pressure in the flexible hoses 21 and 22 depending of course upon the particular bulb which is squeezed. As these bulbs 29 and 30 are of the common type which are used in connection with syringes, they are not illustrated in detail nor are they further described as such is believed

sufficient for those skilled in this art. The hoses 21 and 22 connect with a tube 31 which is to be inserted into the colon of the patient and which is shown somewhat diagrammatically in Fig. 1 and is shown on a larger scale in Fig. 5. The flexible hose 23 is connected to the discharge can 32.

Referring now in more detail to the valve member 15 (see also Figs. 6 to 12 inclusive), the ports 24 and 26 are in casing 18 and are diametrically opposite and likewise ports 25 and 27 are in casing 18 and are similarly aligned. The sleeve member 33 has ports 34 and 36 which are diametrically opposite and which can be moved into and out of alignment with the ports 24 and 26. Also said sleeve 33 has ports 35 and 37 which are diametrically opposite and can be moved into and out of alignment with the ports 25 and 27. Also the sleeve 33 has ports 38 and 39 (see Fig. 4 and also the view to the right of each of Figs. 6 to 12 inclusive) and these ports 38 and 39 can be moved into and out of alignment with the ports 25 and 27. The port 40 in the end wall of sleeve member 33 is movable into and out of alignment with the port 28 in the casing 18 (see Figs. 3, 4 and views to the right in Figs. 11 and 12).

A barrel 41 has a plurality of passageways which are adapted to be moved into and out of alignment with the various ports in sleeve member 33. At the level of the ports 34 and 36 in the sleeve 33, inter-connected passageways 42, 43 and 44 are provided in the barrel 41. The passageway 44 is of much less diameter than the passageways 42 and 43 and is designed for a controlled trickle of liquids therethrough and for purposes hereinafter more specifically mentioned. At the level of the ports 35 and 37 in the sleeve 33, through passageways 45 and 46 are provided and also is provided a passageway 47 inter-connecting with said passageways 45 and 46. Passageway 47A connects to passageway 46 and need not be of as large a diameter as the other passageways. Passageways 45, 46, 47A and 47 are connected with passageways 48 and 49. Passageways 48 and 49 may be moved into and out of registration with port 40 in sleeve member 33 which in turn may be moved into and out of registration with port 28 in casing 18.

The sleeve member 33 is rotatably mounted in the casing 18 and in turn the barrel 41 is rotatably mounted in the sleeve member 33. The said sleeve member 33 has independent means to rotate it and likewise the barrel 41 has independent means to rotate it. As illustrative of a means to rotate the sleeve member 33, pins or projections 50 (Fig. 4) are carried by the sleeve member 33. These pins or projections 50 inter-fit in openings 51 in plate 52. The plate 52 has a hub 53 integral therewith and the hub 53 is mounted for rotary movement on a shaft 54, which said shaft 54, is integral with the barrel 41. Thus the sleeve 33, plate 52 and hub 53 are mounted for relative rotary motion as respects the barrel 41. Means to permit ready rotation of the hub 53 and in turn the sleeve member 33 are provided by a thumb lever 55 which may be threadedly inter-connected with a bore 56 in hub 53.

As an illustration of means to provide ready rotary adjustment of the barrel 41, the shaft 54 is provided with a squared portion 57 and a mating squared opening 58 in lever 59. Nut means 60, is of a size to be detachably secured to the threaded portion 61 of the shaft 54.

In order to assemble the parts from that shown

in exploded relation in Fig. 4, the sleeve member 33 is inserted into the bore of the casing 18. Then the barrel 41 is slidably inserted into the sleeve member 33. Then the plate 52 is inserted in place with the openings 51 thereof registering with the pins or projections 50 carried by the sleeve member 33. Then the cap 62 is threadedly engaged with the threaded portion 63 of casing 18. Next the lever 55 is threaded in the bore 56 of the hub 53. Then the lever 59 is inserted in place with the squared opening 58 thereof registering with the squared portion 57 of the shaft 54. Then the nut means 60 is tightened and all parts are held in the position shown in Fig. 3 of the drawings.

As will appear in Fig. 2 of the drawing, the portion 64, of the lever 59, can be caused to register with the numerals or other appropriate indicia means, as 1 to 5 inclusive, which indicia are on the radially outer portion of the cap 62. The notch 65 registers with suitable indicia means radially inwardly on the cap 62, as indicia means 1 to 3 inclusive: open, emit gas, and shut. Thus the radially inward indicia means indicate the position of the sleeve 33 and the radially outward indicia means indicate the position of the barrel 41.

The tube 31, indicated generally in Fig. 1 of the drawing and shown more in detail Fig. 5, is provided with an inlet opening 66 and a plurality of discharge openings 67. Preferably the inlet opening 66 is at the end portion as indicated and preferably the discharge openings 67 are on the sides as indicated. Thus the muscles and tissue of the colon will not tend to interfere with the inlet of liquids via inlet opening 66, and upon distension of the colon then the openings 67 will be available for discharge of liquid, gases or fecal matter.

The tube 31 may be first inserted in the colon of a patient and then the clean can 13 and soiled can 14 as well as the valve are moved to suitable elevations above the patient with the valve members in the position shown in Fig. 6 of the drawings. There is no flow of liquid past valve 15 as all ports are closed. Thus the desired treating solution may be placed in clean can 13 either before or after the tube 31 is inserted in the colon of the patient. Due to the fact that I have provided for a discharge via openings 67 very little head is required to cause liquid to flow from the clean can 13 into the colon of a patient. In other words by being able to provide for the entrance of liquid and discharge of gases and prevention of building up pressures within a patient, then the liquid may be caused to enter a patient and with very little head. As soon as there is a muscle relaxation, the liquids tend to flow with little or no head as apparently atmospheric pressure is greater than the internal pressure within a patient. Also movement of the diaphragm of the patient apparently changes the internal pressure and the liquid in either clean can 13 or soiled can 14 tends to rise and fall with the diaphragm movement of the patient.

By providing a device where I can cause the liquids at a minimum head to flow to the patient, then I can wait until there is sufficient relaxation of muscles or sufficient diaphragm movement so that the liquids tend to move inwardly into the patient.

Also if the muscles are tense and do not tend to readily relax, then by squeezing bulb 29, additional pressure can be provided to stimulate the muscles so they will relax and permit inflow of

liquid from inlet opening 66. Similarly if fecal matter tends to block the discharge openings 67, then to stimulate flow, the bulb 30 may be squeezed. Of course when either bulb 29 or 30 is squeezed the valve should be closed so that all of the air pressure provided by squeezing of the bulb is in the tube 21 or 22 and does not pass out through the valve 15 to the atmosphere or to any of the particular cans involved. The various foregoing matters have been considered at this point as they are useful in determining the relative elevations of the cans 13 and 14, the valve 15, and the patient.

- The position of the valving parts as indicated in Fig. 6 of the drawing is such that solution will not flow either to or from the patient and may thus be considered an initial position, and thus the apparatus is ready for manipulation to provide the desired treatment. When the parts are 15 in the relative positions shown in Fig. 6 of the drawings, then the portion 64 of the lever 59 registers with the numeral 1 and the notch 65 on the hub 53 registers with the numeral 1 or "open."
- 20 25 The normal positions of the parts during treatment are those indicated in Fig. 7 of the drawings and in such position the portion 64 of the lever 59 registers with the numeral 2 and the notch 65 on the hub 53 registers with the numeral 1. In such position liquids from the clean can 13 flow via tube 16, through port 24 in casing 18, through registering port 34 in sleeve 33, through registering passageway 42 in the barrel 41, through registering port 36 in sleeve 33, 30 through registering port 26 in casing 18, through hose 21, and out via inlet opening 66 in tube 31 to the colon of the patient. At the same time discharge from the patient to the soil can 14 is possible via discharge openings 67 in tube 31, 35 through hose 22, through port 27, through registering port 37, through registering passageway 45, through registering port 35, through registering port 25, and thence via hose 17 to soil can 14. There is no connection to the discharge can 32 40 as passageways 48 and 49 are not in registration with either port 28 or port 40. In Fig. 7 of the drawings, ports 28 and 40 are in registration and thus only the upper port as viewed in the drawings, namely port 40, is numbered.
- 45 50 During the normal position of the apparatus as indicated in Fig. 7 of the drawing, liquids tend to flow from the clean can 13 into the colon of the patient and in due course the liquids then tend to leave the colon and rise in the soil can 55 14. If during treatment it becomes desirable to discharge any material which may enter the soil can 14 and deliver the same to the discharge can 32, the valving parts can be changed to the relative positions shown in Fig. 8 of the drawings.
- 60 65 In this position the portion 64 of the lever 59 registers with the numeral 3 and the notch 65 on the hub 53 registers with the numeral 1 or the indicia "open." In such position, there is no flow between the clean can 13 and the patient 70 as the barrel 41 blocks any flow between ports 34 and 36. At the same time discharge from the soil can 14 to discharge can 32 is permitted, as a liquid may flow from soil can 14 via tube 17, through port 25, through registering port 35, through registering passageway 47, through port 49, through registering port 40, through registering port 28, and thence via hose 23 to discharge can 32. At the same time liquids from clean can 13 are blocked from entering hose 21 as the barrel 75 rei 41 blocks the ports 35 and 37.

If it becomes desirable during treatment to lower the back pressure caused by the elevation of soil can 14, or if it should be desired to use the treating solution only once, then the valving part can be moved to assume the relative positions shown in Fig. 9 of the drawings. In this position the portion 64 of the lever 59 will register with numeral 4 and the notch 65 will register with the numeral 1 or "open." In this position liquids from the clean can 13 flow via tube 16, through port 24 in casing 18, through registering port 34 in the sleeve 33, through registering passageway 43 in the barrel 41, through registering port 36 in the sleeve 33, through registering port 26, through hose 21 and out via inlet opening 66 in the tube 31 to the colon of the patient. At the same time discharge from the patient to the discharge can 32 is possible via discharge openings 67 in tube 31, through hose 22, through port 27, through registering port 37, through registering passageway 46, through passageway 48, through registering port 49, through registering port 28, and thence via hose 23 to discharge can 32. At the same time liquids may flow from the soil can 14 to the discharge can 32 via tube 17, through port 25, through registering port 35, through registering passageway 46, through passageway 48, through registering port 46, through registering port 28, and thence via hose 23 to discharge can 32.

During treatment it is often desirable to provide a dribble or trickle flow of liquid from the clean can 13 to the patient and to provide for a gas escape from the patient to the discharge can 32. At many times the dribble or trickle stream will be such that it will be absorbed by the tissues of the patient and merely gas will flow from the patient to the discharge can 32. Also at times there may be a slight discharge of liquid as well as gases from the patient to the discharge can 32. In such position the valving parts will be in the position shown in Fig. 10 of the drawings. There will be a connection from the clean can 13 to the patient and a connection between the patient and the discharge can 32. The soil can 14 will not be connected to any other can or to the patient. In such position the portion 64 of the lever 59 will register with the numeral 5 and the notch 65 will register with the numeral 3 or "open." In such position liquids from the clean can 13 flow via tube 16, through port 24, through registering port 34 in sleeve 33, through registering passageway 44 in the barrel 41, through registering port 36 in the sleeve 33, through registering port 28 in the casing 18, through hose 21, and out via inlet opening 66 in the tube 31, to the colon of the patient. At the same time discharge from the patient to the discharge can 32 is possible via discharge openings 67 in tube 31 through hose 22, through port 27, through port 37, through registering passageway 47A, through passageway 46, through registering passageway 48, through partially registering port 49, through registering port 28, and thence via hose 23 to discharge can 32.

If during treatment it becomes desirable to have an emergency relief of gas and this without any connection between the clean can and the patient, this may be obtained by the relative positions of the valving parts as shown in Fig. 11. In such position the portion 64 of the lever 59, registers with the numeral 2 and the notch 65 registers with the numerals 2 or with "emit gas." In this position gas may flow from the patient through openings 67 in tube 31, through hose 22, through port 27, through registering port 37,

through passageway 45, through registering port 35, through registering port 25, and thence via hose 27 to soil can 14. In this position there is no connection between the patient and clean can 13. There is a small discharge possible from the patient to discharge can 32 as gas in passageway 45 enters passageway 49, thence port 40, thence port 28 (ports 40 and 28 are overlapped) and thence through hose 23 to can 32.

If during treatment it is desired to remove the barrel 41 and yet at the same time to maintain all ports closed, this can be accomplished by turning the various valving parts to the positions shown in Fig. 12 of the drawing. This position accomplishes all of the purposes of the position shown in Fig. 6 but the additional purpose of permitting removal of the barrel 41. In this position the sleeve 33 blocks passageway between ports 24 and 26 and also between ports 25 and 27. The ports 28 and 40 may or may not be in registration and hence there may or may not be communication between the valve and the hose 23. As the discharge can 32 is below the valve 15, ports 28 and 40 need not be out of registration to prevent flow from discharge can 32 to valve 15. The parts assume the relative positions of Fig. 12 with portion 64 of lever 59 registering with any numeral (in Fig. 12 it registers between numerals 2 and 3) and notch 65 registers with numeral 3 or 20 shut. In other words, sleeve 33 has been angularly moved to block passage between hoses 16 and 24 and between hoses 17 and 22 regardless of the position of barrel 41. Thus during operation of the apparatus the barrel 41 can be moved for cleaning processes and then re-inserted after being cleaned and the process can be again resumed without the necessity of draining liquids from the apparatus.

From the foregoing it is obvious that I have provided apparatus so that desired medicated solutions can be used in enemas and the same can be placed in the apparatus before or after a tube is inserted into the colon of a patient. The tube of my invention is provided with both inlet and outlet means so that the incoming solutions can displace gas and obviate the building up of air or gas pressures or permit the release of any such if they are built up without interruption of the treatment. This is of substantial value as the liquids may gradually enter the patient and with very little head so that the muscles of the patient can gradually relax and there will be a gentle inward flow of treating solution to the patient and a gradual discharge of solution and material from the patient. This flow, in many instances, follows the diaphragm action of the patient and has not occurred in prior art apparatus where we merely have an inflow of liquids and inherent compression of air or gas in the patient to permit such inflow of liquids. Inflow of liquids, without gas or air relief means to keep pressures down, results in stimulation of organs and muscles and counteracts any tendency of the diaphragm action to cause liquids to have a modulated and gentle inflow and outflow.

Next the apparatus permits disposal of any used solutions and their replacement without removal of the tube from the patient or the reuse of treating solutions.

Next the apparatus permits treating liquids to be used only once, when desired, and with a minimum back pressure to their discharge.

Next the apparatus permits a regulated minimum inflow of liquids which will either gradually add to the supply of treating liquids or merely

supply enough liquids to replace liquids absorbed by the body. At the same time the apparatus permits gas discharge and at a minimum back pressure.

Next the apparatus provides for an emergency gas relief which may be needed and again without disconnection of the apparatus from the patient.

Next the apparatus permits removal of the barrel of the valve for cleaning and without removal of liquids from the apparatus of disconnection of the same.

Next the apparatus is provided with air pressure providing means to stimulate inflow and/or outflow from the patient.

Obviously changes may be made in the forms, dimensions, arrangements and manipulations of the parts of my invention without departing from the principles thereof as defined in the claims of this application.

I claim:

1. Enema apparatus comprising a receptacle for clean enema treating solutions; a receptacle for soiled enema treating solutions, the bottom of which is disposed at an elevation relatively close to and below the bottom of said first mentioned receptacle; a receptacle for the disposal of soiled enema treating solutions disposed at an elevation below that of said first two mentioned receptacles; a tube having inlet and outlet passageways and disposable in the colon of a patient at an elevation below said first two mentioned receptacles and above said last mentioned receptacle; a plurality of conduit means connecting each of said receptacles with said passageways in said tube; and an adjustable valve means connected with said conduit means and providing variable closed and open passageways between said passageways in said tube and said receptacles, said valve means being adjustable to provide communication between the receptacle for clean treating solutions and a patient and to provide communication between the patient and the receptacle for soiled treating solutions and to block communication to the receptacle for the disposal of treating solutions.

2. Enema apparatus comprising a receptacle for clean enema treating solutions; a receptacle for soiled enema treating solutions, the bottom of which is disposed at an elevation relatively close to and below the bottom of said first mentioned receptacle; a receptacle for the disposal of soiled enema treating solutions disposed at an elevation below that of said first two mentioned receptacles; a tube having inlet and outlet passageways and disposable in the colon of a patient at an elevation below said first two mentioned receptacles and above said last mentioned receptacle; a plurality of conduit means connecting each of said receptacles with said passageways in said tube; and an adjustable valve means connected with said conduit means and providing variable closed and open passageways between said passageways in said tube and said receptacles, said valve means being adjustable to provide communication between the receptacle for soiled treating solutions and the receptacle for the disposal of soiled treating solutions and to block communication between the patient and all of the receptacles.

3. Enema apparatus comprising a receptacle for clean enema treating solutions; a receptacle for soiled enema treating solutions, the bottom of which is disposed at an elevation relatively close to and below the bottom of said first mentioned receptacle; a receptacle for the disposal

of soiled enema treating solutions disposed at an elevation below that of said first two mentioned receptacles; a tube having inlet and outlet passageways and disposable in the colon of a patient at an elevation below said first two mentioned receptacles and above said last mentioned receptacle; a plurality of conduit means connecting each of said receptacles with said passageways in said tube; and an adjustable valve means connected with said conduit means and providing variable closed and open passageways between said passageways in said tube and said receptacles, said valve means being adjustable to provide communication between the receptacle for clean treating solutions and a patient and between a patient and the receptacle for soiled treating solutions and the receptacle for the disposal of soiled treating solutions.

4. Enema apparatus comprising a receptacle for clean enema treating solutions; a receptacle for soiled enema treating solutions, the bottom of which is disposed at an elevation relatively close to and below the bottom of said first mentioned receptacle; a receptacle for the disposal of soiled enema treating solutions disposed at an elevation below that of said first two mentioned receptacles; a tube having inlet and outlet passageways and disposable in the colon of a patient at an elevation below said first two mentioned receptacles and above said last mentioned receptacle; a plurality of conduit means connecting each of said receptacles with said passageways in said tube; and an adjustable valve means connected with said conduit means and providing variable closed and open passageways between said passageways in said tube and said receptacles, said valve means being adjustable to provide restricted communication between a receptacle for clean treating solutions and a patient and restricted communication between a patient and the receptacle for the disposal of soiled treating solutions and to block communication to the receptacle for soiled treating solutions.

5. Enema apparatus comprising a receptacle for clean enema treating solution; a receptacle for soiled enema treating solutions, the bottom of which is disposed at an elevation relatively close to and below the bottom of said first mentioned receptacle; a tube having inlet and outlet passageways and disposable in the colon of a patient at an elevation below said two receptacles; a plurality of conduit means interconnecting said receptacle for clean solutions with said inlet passageway and interconnecting said receptacle for soiled solutions with said outlet passageways; and adjustable valve means disposed in said conduit means, said valve means having valving members disposed between said receptacle for clean treating solutions and said inlet passageway and between said receptacle for soiled treating solutions and said outlet passageway, said valve means being adjustable to provide emergency gas relief between a patient and the receptacle for soiled treating solutions and to block communication between the patient and said receptacle for clean treating solutions.

6. Enema apparatus comprising a receptacle for clean enema treating solutions; a receptacle for soiled enema treating solutions, the bottom of which is disposed at an elevation relatively close to and below the bottom of said first mentioned receptacle; a tube having inlet and outlet passageways and disposable in the colon of a patient at an elevation below said two receptacles; a plurality of conduit means interconnecting said

receptacle for clean solutions with said inlet passageway and interconnecting said receptacle for soiled solutions with said outlet passageway; and adjustable valve means disposed in said conduit means, said valve means having valving members disposed between said receptacle for clean treating solutions and said inlet passageway and between said receptacle for soiled treating solutions and said outlet passageway, said valve means comprising a casing having an internal bore and having ports therein, an annular sleeve mounted for angular movement in said casing and having ports movable into and out of registration with the ports in the casing, and a barrel mounted for angular movement in said sleeve and having ports movable into and out of registration with the ports in said sleeve, whereby the sleeve can

block the ports in the casing and the barrel can be removed without unblocking the ports in the casing.
